UNITED STATES PATENT OFFICE.

ROBERT LEE LEATHERMAN AND FRANK PFROGNER, OF MOUNT PLEASANT, PENNSYLVANIA.

ADJUSTABLE SEAT AND DESK.

1,324,560.

Specification of Letters Patent.

Patented Dec. 9, 1919.

Application filed July 17, 1917. Serial No. 181,164.

To all whom it may concern:

Be it known that we, ROBERT L. LEATHERMAN and FRANK PFROGNER, citizens of the United States, residing at Mount Pleasant, 5 in the county of Westmoreland and State of Pennsylvania, have invented certain new and useful Improvements in Adjustable Seats and Desks, of which the following is a specification.

10 This invention has relation to adjustable school desks, and has for an object to provide a desk, with means whereby a vertical adjustment of the desk is permitted, to adapt the same to the size of the pupil.

15 Another object of the invention is to provide a desk, particularly for school purposes, embodying a desk top mounted for vertical adjustment with means readily operable for adjusting the height of the top, and a novel 20 means for retaining the top in its adjusted position.

In addition to the foregoing, this invention comprehends improvements in the details of construction and arrangement of 25 parts to be hereinafter described and particularly pointed out in the appended claim.

30 In the accompanying drawings in which similar and corresponding parts are designated by the same characters of reference throughout the several views in which they appear:—

Figure 1 is a view in side elevation of an improved desk as associated with a chair.

35 Fig. 2 is a view of the desk in front elevation.

Fig. 3 is a vertical section taken centrally through the desk.

Fig. 4 is a detail section taken on the line 40 4—4 of Fig. 2.

With reference to the drawings, and particularly to the construction of the desk, 10 indicates the end frame members of the desk, each of which comprises vertical, 15 transversely spaced castings 11 and 12 at the front and rear sides respectively. The castings 11 are of openwork construction, extending approximately the full width of the desk, and provided with vertical slots 13 and 14 at the front and rear edges of the castings respectively. The rear castings 12 are in the nature of vertical strips which are formed with outwardly extending apertured ears 15 upon their inner edges for coaction 20 with similar ears 16 formed on the rear

edges of the castings 11, bolts 17 being provided to penetrate the ears whereby to hold the castings together. It will be noted that the castings 11 and 12 are each formed with legs 18 and 19 respectively, which diverge 60 when the castings are connected, and which are formed with feet 20 whereby the frame members may be rigidly secured to the floor.

A desk top designated as an entirety at 21 is provided, and includes a top board 22 and a bottom board 23, connected by side boards 24 in a manner to dispose the top and bottom in spaced relation, and to dispose to top board at an inclination. A back board 25 is provided to close the back of the desk top, 70 and it will be noted that said back board extends vertically above and below the desk top and beyond the sides thereof. A pair of cleats 26 are furthermore secured to the side boards at the front and rear ends as indicated. The cleats 26 are designed to enter the slots 13 and 14 of the frame, and the vertical edges of the back board are designed to enter the space between the castings 11 and 12 of the end frame members, 80 whereby the desk top is guided for vertical movement.

A horizontal shaft 27 is journaled at its ends in the castings 11 of the end frame members adjacent the rear edges thereof, 85 and at a point about midway of the height thereof. A gear wheel 28 is fixedly mounted upon the shaft at a point intermediate its ends for engagement with a rack bar 29 secured to the inner face of the back board 90 beneath the desk top. A crank handle 30 is secured to one end of the shaft whereby the shaft may be rotated, and a ratchet wheel 31 is secured to the shaft for engagement with a pawl pivoted to the adjacent frame 95 whereby to prevent reverse rotation of the shaft when the same is rotated to raise the desk top.

Thus it will be seen, the desk top may be raised or lowered to adjust its height to 100 the size of the user, and the desk will be retained in adjusted position temporarily by means of the pawl and ratchet. However, to secure the desk in its adjusted position and to provide a more positive support to 105 resist downward strain upon the desk top, the bolts 17 are tightened so as to cause the castings 11 and 12 to tightly engage and bind the edges of the back board therebetween.

The seat should be so constructed that the pins 39 will be in recesses when the seat is adjusted squarely in front of the desk, so that when the user rises and the seat 5 is relieved of his weight, the top and intermediate boards may be rotated relative to the bottom board, thereby permitting the seat to be turned when the pupil or user is leaving or approaching the desk. The pins 10 may be seated in the recesses again by rotating the seat a quarter of a revolution.

Thus it will be seen that we have provided a novel combination of elements in the construction of this desk, which is especially adapted for use in schools, permitting such adjustments of the chair and desk so as to insure the correct hygienic position of the pupil before the desk, thereby preventing many deformities and causes of ill health 20 which are the result of an incorrect posture.

While we have illustrated and described our invention with some degree of particularity, we realize that in practise various alterations and changes may be made, and 25 we therefore reserve the right and privilege of changing the form of the details of construction and otherwise altering the arrangement of the correlated parts, without

departing from the spirit of the invention or the scope of the appended claim. 30

Having thus described our invention, what we claim as new and desire to secure by Letters Patent is,—

A desk including a pair of end frames each having a vertically disposed slot therein, a desk-top having extensions slidably engaging said slots, a rack carried by said desk-top, a shaft rotatably mounted in said frames, a gear mounted on said shaft, a ratchet wheel on said shaft adjacent one end 35 thereof, a pawl pivotally secured to one of said frame members and engaging said ratchet wheel, a backboard carried by said desk-top and extending to the outer surfaces of said frame members, rear castings spaced 40 from said frame members, and means securing said rear castings to said frame members and binding said back-board of the desk.

In testimony whereof we affix our signatures in the presence of two witnesses.

ROBERT LEE LEATHERMAN.
FRANK PFROGNER.
